UNITED STATES PATENT OFFICE.

CHARLES MORTON BOBBITT, OF ALMA, NEBRASKA.

CORN-HUSKING IMPLEMENT.

1,161,020.

Specification of Letters Patent. Patented Nov. 23, 1915.

Application filed December 10, 1914. Serial No. 876,412.

To all whom it may concern:

Be it known that I, CHARLES MORTON BOBBITT, a citizen of the United States, residing at Alma, in the county of Harlan and 5 State of Nebraska, have invented a new and useful Corn-Husking Implement, of which the following is a specification.

My invention relates to the husking of corn by hand and is a departure from the 10 ordinary method of husking, in that the husking peg or implement is attached to the back of the hand.

The object of this is to eliminate extra motions and to tear the husk from the corn 15 in the same forward movement that is necessary in grasping the ear.

All references herein made to the drawing refer to the new drawing, filed June 8, 1915, and the following is an exact description 20 of said implement, which will enable others skilled in the art to which it appertains to make use of the same, reference being had to the drawings and the figures of reference marked thereon, which form a 25 part of this specification.

My invention pertains to corn-husking implements and consists in the implement hereinafter described and claimed, specifically 30 constructed with a view of being applied on the back of the hand, before or subsequent to the placing of a mitten thereon, and of being used to advantage over the mitten and of eliminating one or more motions in the 35 husking of each ear of corn.

35 In the new drawings, accompanying and forming a part of this specification: Figure 1 is a perspective view of husking pin from the side, showing my novel implement as properly arranged on the hand; also, showing by dotted lines the position of the hand of the user relative to the implement when properly attached. Fig. 2 shows a perspective view of the leather pad (3) with straps (4) thereto attached, whereby the 40 implement is attached to the hand. Fig. 3 is a plan view of a portion of my device taken from above showing the method of attaching the blade or husking pin (1) to the foundation plate (2), and of attaching the 45 foundation plate to the leather pad (3). Fig. 4 is a section through the rear end of the pin showing the method of making such fastening.

50 My novel corn-husking implement is 55 formed of one or more pieces of steel or of

other metal suitable for the purpose, which may be attached and fastened to the hand by means of a leather pad and leather straps or other similar means as indicated by Fig.

1. Where two pieces of metal are used, 60 they are of about the proportionate length and size indicated in Figs. 1 and 3. The pin (1) being properly curved to conform to the shape of the hand, and holes therein being made to conform to the bolt holes in 65 the foundation plate (2), and there being several holes in the pin so that the same may be lengthened or shortened to conform to the length of the hand of the user, the point of same being curved as illustrated in Fig. 70 1, and pointed so as to penetrate the husks of the ear of corn and separate them from the ear. The foundation plate (2) is of approximately the size indicated in Fig. 3, and has proper holes for fastening it to the 75 leather pad and two holes for the bolts (5) by which the pin is attached. The foundation plate (2) is slightly curved to conform to the shape of the back of the hand. The implement is attached to the hand by straps 80 (4) or other means as indicated in Fig. 1 and may be used with or without glove or mitten.

85 In using my implement the operator applies the implement to the back of the hand and fastens the same in place by the leather straps and buckles (4). The bolts (5) should be adjusted in the holes in the base of the pin (1) so that the curved point of the pin extends slightly beyond the operator's hand. When the implement is so fastened, the blade of the pin extends down the back of the hand parallel with the second finger, and the base of the foundation plate 90 (2) rests on the leather pad (3) on the back of the hand opposite the thumb. Being thus fastened, no grasping of the implement is necessary. The husks on one side of the ear of corn are separated from the ear by a forward movement of the hand, the pin being so directed as to separate the husks from the ear and slide them over the back of the hand. The ear of corn is then 95 grasped by the hand on which the implement is placed, the remaining husks on the ear of corn are grasped by the other hand and the ear is jerked from its shank by the hand upon which the implement is fastened.

100 It will be noticed from the above description that the husking of an ear of corn with 105 110

my implement requires one less motion than with the ordinary corn-husking implement used on the palm of the hand.

What I claim is:

As a new article of manufacture the herein described corn-husking implement, consisting essentially of a blade and foundation therefor conforming to the back of the hand and sufficiently long when in place to ex-

tend beyond the ends of the fingers, with adjustable means whereby the blade may be lengthened or shortened to conform to the length of the hand of the wearer and means for attaching to the back of the hand.

CHARLES MORTON BOBBITT.

Witnesses:

GEORGE M. BOEHLER,

ERMA SCHERBACHER.
